UNITED STATES PATENT OFFICE.

EDWIN WILBUR RICE, JR., OF LYNN, MASSACHUSETTS.

MOTOR-SUSPENSION FOR RAILWAY WORK.

SPECIFICATION forming part of Letters Patent No. 448,260, dated March 17, 1891.

Application filed August 15, 1889. Serial No. 320,905. (No model.)

To all whom it may concern:

Be it known that I, EDWIN WILBUR RICE, Jr., a citizen of the United States, and a resident of Lynn, in the county of Essex and 5 State of Massachusetts, have invented certain new and useful Motor-Suspension for Railway Work, of which the following is a specification.

My invention relates to the manner of 10 mounting or supporting electric motors when applied to the propulsion of railway-cars.

The objects of my invention are to secure 15 rigidity, strength, and an unvarying relation of motor and driving-axle of the car, as well as accessibility for purposes of repair and an automatic adjustment of the commutator for variations of lead in different conditions of working.

My invention relates particularly to those 20 methods of suspension or support for the motor in which such motor is in part supported by an axle of the car.

The principal part of my invention consists 25 in the provision of a frame sleeved to the car-axle and provided with journal-bearings for the armature-axis and the axes of any intermediate gear between the armature and car-axle, the motor field-magnet being supported on the armature-axis, as will be hereinafter 30 more particularly set forth.

My invention consists, also, in the novel 35 construction and mounting of the frame itself, whereby I secure great rigidity.

My invention consists, also, in other features of construction and combinations of parts, hereinafter described in connection with the accompanying drawings, and then more particularly specified in the claims.

In the accompanying drawings, Figure 1 is 40 plan, and Fig. 2 a side elevation, of apparatus embodying my invention. Fig. 3 is a side elevation of a modified manner of supporting the parts of the apparatus.

F indicates a frame of brass, iron, or other 45 suitable material, consisting of two side or longitudinal pieces and a cross-piece, as shown, all cast or formed in one piece. The side pieces F are sleeved or journaled upon the axle I of the car or vehicle, and are provided likewise with journal-bearings for the 50 axes E E². The removable caps of such journal-bearings are indicated at T.

A A indicate the field-magnet of an electric motor, H the field-magnet poles of the same, and D the armature mounted on the armature-shaft E. The armature-shaft is connected through suitable intermediate gear with the car-axle I, as well understood in the art. The shaft of such intermediate gear is indicated at E². 55 60

The frame F, being supported at one end by the car-axle I, is elastically supported at its other end by some portion of the truck-frame K. For this purpose the cross-bar F is mounted between springs or cushions I² I², 65 supported in the frame K, as indicated. The field-magnet is supported at one end on the armature-shaft E by sleeves P P, preferably of brass or other non-magnetic material, which are carried by extensions from the field-magnet pole-pieces H, as shown. The opposite end of the field-magnet may be supported in any desired manner. I prefer to support it elastically from the car-body or from the truck-frame—as, for instance, by means of an 70 elastic support, such as indicated at C, Fig. 1, or by a flexible ball-and-socket joint, as indicated at L, Fig. 3. It will be observed that by means of this support for the motor, independent of the frame carrying the bearings 75 therefor, said frame is relieved of the weight of the motor and the weight is transferred to a support independent of such frame, while the rigid motor-frame around the motor preserves an accurate alignment of the armature-shaft and the driven axle of the vehicle. 80 85

The particular manner of supporting the yoke-end of the field-magnet elastically or flexibly does not form any part of my present invention, and other means besides those shown 90 may be employed in connection with the particular means hereinafter described for supporting the opposite end of the motor. Other special devices may be employed instead of those shown for supporting the end of the 95 motor independently of the motor-frame. 100

The commutator-brushes of the machine are carried by a yoke N, supported by the frame F, instead of by the field-magnet or extensions from the pole-pieces thereof. The brush-arm extends over the sleeve P and arms, carrying the same into the open space between the latter and over the commutator-cylinder.

It is well-known that in a motor the lead is negative or opposite to that of a generator. Unless some means is provided for varying the position of the brushes upon the commutator sparking will occur with changes of load and particularly when a reversal in the direction of rotation takes place. By this method of suspension and mounting of the brush-support this tendency to sparking is automatically compensated for by the rotation of the field-magnets about the armature. It will be noticed that when a heavy load comes on, the motor-frame will be depressed or raised according to the direction of rotation of the armature, and as one end of the field-magnet is relatively fixed in position the field-magnet and armature will occupy different positions with respect to each other when the motor-frame is raised or depressed. This change of position of the field and armature with relation to each other is such (the brushes moving with the motor-frame) that the effect is practically the same as a backward lead given to the brushes as the load comes on—that is, a heavy load rotates the field forward in the direction of revolution of the armature.

By my construction of supporting-frame and mounting of the parts, hereinbefore described, I not only secure stiffness and rigidity when the apparatus is subjected to strain, but also an adaptation of the mechanism to vibrations, jars, or movements of the car and supporting parts, which will maintain the mechanism in unchanged relation during all conditions of working. I am, moreover, enabled to secure ready accessibility to the electric motor, since by simply removing the journal-bearing caps T the entire motor can readily be taken out through a trap in the car-floor for making necessary repairs or for any other purpose.

What I claim as my invention is—

1. In an electric-railway motor, the combination of a motor field-magnet sleeved at one end on its armature-shaft, and an armature-shaft journaled in an independent frame carried at one end by an axle of the car and at its other by the truck-frame.

2. The combination, substantially as described, of the journal-bearing frame for the armature elastically supported at one end and sleeved to an axle of the car at the other, and a field-magnet supported on the armature-axis and at its other by an independent support.

3. The combination of the frame sleeved at one end on an axle of the car and supported at its other end by the truck-frame, of a motor-armature journaled in said frame, and a motor field-magnet supported at one end by the armature-axis and at the other by the car-body.

4. The combination, with the supporting-frame sleeved at one end on an axle of the car and elastically supported at its other, of a motor-armature journaled in said frame, and a motor field-magnet carried at one end

by supporting-sleeves on the armature-axis and at its other by an attachment to the car-body.

5. The combination, with the supporting-frame sleeved at one end on the driving-axle and elastically supported at its other, of an armature and gear journaled in said frame, and a field-magnet having a non-magnetic supporting sleeve or sleeves at one end borne by a shaft journaled in the frame, as and for the purpose set forth.

6. The combination, substantially as described, of the frame F , sleeved at one end on the driving-axle and elastically supported at its other, of a motor field-magnet supported at its yoke end in any suitable manner and having its field-pole end supported by the armature-shaft, journal-bearings for said shaft carried by the frame near its elastically-supported end, and a commutator-brush support mounted on said frame.

7. The combination, in an electric-railway motor, of a supporting-frame sleeved at one end on the car-axle and a driving electric motor supported at one end by the armature-axis of the motor journaled in said frame and at its other independently of said frame.

8. The combination, in an electric-railway motor, of a supporting-frame sleeved at one end on the car-axle, and a driving electric motor supported at one end by an axis that is journaled in the frame and at its other independently of said frame.

9. In an electric-railway motor, the combination, substantially as described, of a motor-frame in which the armature of the motor is mounted, and a support for the motor independent of such frame, as and for the purpose described.

10. In an electric-railway motor, the combination, substantially as described, of a frame provided with bearings for the gear which transmits motion from the armature to the car-axle, in combination with an independent elastic support for the motor sustained independently of said frame.

11. The combination, in an electric-railway motor, of a frame sleeved on the car-axle, and an elastic support independent of said frame and sustaining the field-magnet.

12. The combination, in an electric-railway motor, of a rigid frame for holding the parts in proper alignment with the car-axle, and a spring-support independent of said frame, whereby the frame may be relieved of the weight of the motor.

13. The combination, in an electric-railway motor, of a pivoted frame sustaining the armature, and a field-magnet sustained on pivoted bearings at one end carried by the frame and at the other by a support independent of the frame at the outer end.

14. In an electric-railway motor, an armature and gear supporting frame formed of two side pieces and a cross-piece integral with one another and constituting a continuous frame independent of the motor, said frame

being sleeved at one end upon an axle of the car and elastically supported at its other end on the same side of said car-axle with the electric motor sustained by said frame.

5 15. The combination, in an electric-railway motor, of a supporting-frame in which the armature of the motor is journaled, and a field-magnet for said armature supported at one end by non-magnetic brackets sleeved on the armature-shaft.

16. The combination, substantially as described, of the gear and armature supporting frame carried by the truck-frame and car-axle, and a motor field-magnet supported at 15 one end by the armature-shaft.

17. In an electric-railway motor, the combination of a supporting-frame provided with journal-bearings for the armature-shaft of the motor, and a motor field-magnet supported on 20 the armature-shaft by sleeves thereon and by supports attached to the truck-frame or car-body.

18. The combination, in an electric-railway motor, of a field-magnet having its field-pole 25 end freely supported so as to be movable by change of load, a movable supporting-frame therefor, and a commutator-brush support

carried by the movable frame supporting the field-magnet, as and for the purpose described.

30

19. In an electric-railway motor, a rigid supporting-frame for the armature and gear shafts, said frame consisting of two longitudinal or side pieces sleeved on an axle of the car and carrying the journal-bearings for said shafts, and a cross-piece, said side and cross pieces being integral and forming three sides of a continuous frame independent of the motor, as and for the purpose described.

35 20. In an electric-railway motor, a rigid supporting-frame for the electric motor, consisting of the side or longitudinal pieces sleeved to an axle of the car and a uniting cross-piece integral with them, said side and cross pieces forming three sides of a continuous frame independent of the motor.

Signed at New York, in the county of New York and State of New York, this 7th day of August, A. D. 1889.
